(57) **CLAIM**

An ornamental design for blister envelope for blister packings, as shown and described.

DESCRIPTION

FIG. 1 is a top plan view of a blister envelope for blister packings in accordance with the present invention;

FIG. 2 is a top, front and right side perspective view thereof; FIG. 3 is a right side elevational view thereof, the left side elevational view being a mirror image;

FIG. 4 is a front elevational view thereof, the rear elevational view being a mirror image;

FIG. 5 is a second top, front and right side perspective view thereof; and,

FIG. 6 is a top, front and left side perspective view thereof.
